UNITED STATES PATENT OFFICE.

LAWRENCE W. HANNON, OF IRONTON, OHIO.

COMBINED GRAVITY AND VACUUM STEAM TRAP.

Application filed August 31, 1927. Serial No. 216,729.

A grave danger exists in the operation of low pressure steam engines by reason of the back pressure caused by saturated steam leaving the engine. The back pressure thus caused is a source of serious trouble, which in some instances results disastrously to the engine.

The present invention provides a trap for eliminating the excessive moisture from the 10 exhaust of a low pressure steam engine, said trap being adapted for automatic or manual operation and by gravity and vacuum, said trap consisting of a closed tank of suitable capacity disposed at a lower level than the 15 low pressure engine to admit of the condensate flowing thereto from the engine by gravitational action and assisted by the suction resulting from exhausting the air from the tank.

20 An embodiment of the invention is shown in the accompanying drawing which is a side view of a trap and adjunctive parts, a portion of the tank being broken away to show the float therein.

25 The tank is designated by the numeral 1 and may be of any capacity and construction, and is located at a lower level than the low pressure steam engine with which it is associated. For convenience, the trap is 30 shown located within a sump or pit 2. A pipe 3 connects the tank 1 with the exhaust of the low pressure engine, not shown, and this pipe is provided in its length with a valve 4. A pipe 5 leading from the tank 1 35 is connected to an air pump, not shown, whereby air may be exhausted from the tank to create a vacuum therein. The pipe 5 is provided in its length with a controlling valve 6 and a pressure indicating gage 7.

40 The numeral 8 designates a vent pipe which is connected with the top of the tank 1, and which is provided with a valve 9. A gage 10 is connected with the tank 1 for indicating the level of the water therein. One end 45 of the gage 10 is connected directly with the tank, whereas the opposite end is connected to the vent pipe 8. A pipe 11 connects with the bottom portion of the tank 1 and is provided with a valve 12. A pump 13 has the

50 pipe 11 connected thereto, and a discharge pipe 14 leads from the siphon to convey the water to a convenient point of discharge. The siphon 13 may consist of a rotary pump and motor which is adapted to be operated by steam from the boiler, not shown, supplied thereto by means of a pipe 15. A

pipe 16 connects with the pipe 11 at a point between the valve 12 and siphon 13, and is provided in its length with a valve 17. A pump 18 is connected with the bottom of 60 the tank 1 by means of a pipe 19 in the length of which is located a manually operable valve 20 and a check valve 21. A pipe 22 connects the pump 18 with the boiler, not shown, to supply the condensate thereto as 65 feed water from the tank 1. The feed pipe 22 is provided with a manually operable valve 23 and a check valve 24, the latter being automatic in action to prevent loss of water from the boiler. The check valve 21 70 is also automatic in action. A steam pipe 25 supplies the motive medium for operating the pump 18 and connects with the boiler or other source of supply, not shown. The pipe 25 is provided with a valve 26 75 which is adapted to be operated automatically, or by hand, as desired. A lever 27 is connected with the movable part of the valve 26 and is weighted at its outer end, the weight 28 being connected thereto by means 80 of a chain, or in any other determinate way. A flexible connection 29 is coupled at one end to the lever 27 and passes over guide pulleys 30 and 31 and is connected at its opposite end to a stem 32 projecting from a 85 float 33 and operating in a stuffing box 34 at the top of the tank 1. The float 33 is disposed within the tank 1 and the guide pulleys 30 and 31 give proper direction to the flexible connection 29. The weight of 90 the float 33 is in excess of the weight 28, hence, when the float is at a low level within the tank 1, the weight 28 is elevated and the valve 26 closed, but when the float 33 is elevated by a rise of the water in the tank 1, 95 the weight 28 descends and operates to open the valve 26, thereby admitting steam to the pump 18, whereby to pump the water from the tank 1 and force it as feed water into the boiler through the pipe 22 upon opening 100 the valve 23. When the float 33 descends the valve 26 is automatically closed, thereby cutting off a supply of steam or other motive medium to the pump 18.

When the valve 4 is open the condensate 105 from the low pressure engine will flow by gravity through the pipe 3 into the tank 1. This gravitational action may be assisted by creating a partial vacuum within the tank 1. This is effected by closing the valves 9 and 110 12, it being assumed that the valve 20 has also been closed. Upon opening the valve 6

and starting the air pump to which the pipe 5 is connected air will be exhausted from the tank 1, thereby creating a partial vacuum therein, the degree being indicated by the 5 gage 7. After a sufficient quantity of air has been exhausted from the tank 1 to create a vacuum therein the valve 6 is closed, and the valve 4 opened, and as a result the condensate from the engine flows through the 10 pipe 3 into the tank 1 both by gravitational action assisted by a suction, as a result of the vacuum which has been created within the tank 1. Water may be drawn from the tank 1 and from the sump or pit 2 by means 15 of the rotary pump 13, and discharged through the pipe 14 at a determinate point.

Having thus described the invention, I claim:

In an apparatus of the character described, the combination of a closed tank, 20 means to support the tank at a level lower than an engine with which the apparatus is to cooperate, a pipe leading from the upper portion of the tank for connection with the 25 exhaust of the engine and having a manually controlled valve in its length, a second pipe leading from the upper portion of the

tank for connection with a suction pump whereby a partial vacuum may be created in the tank and having a manually controlled valve in its length, a float in said tank having an upstanding stem extending outwardly through the upper portion of the tank, a water pump below said tank, a steam pipe leading from said pump for connection 30 with a boiler to supply steam to the pump to actuate the same, a valve in the steam pipe having an actuating lever, a body of less weight than the float suspended from the lever to move the lever downwardly and 40 open the valve when the float is raised, a flexible connection between the lever and stem of said float to close the valve when the float is lowered, a pipe connecting said pump with said tank to conduct water from 45 the tank to the pump and having a manually controlled valve and a check valve in its length, and a pipe for delivering water to the boiler leading from the pump and having a manually controlled valve and a 50 check valve in its length.

In testimony whereof I affix my signature.

LAWRENCE W. HANNON. [L. W. H.]
